UNITED STATES PATENT OFFICE.

ELLERY PERRY, OF OLEAN, NEW YORK, ASSIGNOR OF ONE-HALF TO ROY E. VANCE, OF OLEAN, NEW YORK.

RAILROAD TIE.

Application filed December 23, 1924. Serial No. 757,723.

To all whom it may concern:

Be it known that I, ELLERY PERRY, a citizen of the United States, and a resident of Olean, in the county of Cattaraugus and 5 the State of New York, have invented new and useful Improvements in Railroad Ties, of which the following is a specification.

An object of my invention is the provision of a railroad tie which will keep the rails 10 equidistantly spaced and which will provide a cushion like riding means.

Another object of my invention is to provide a locking means for a railroad tie which is effective, durable and positive.

15 A still further object of my invention is the provision of a single or double tie construction for railroads which is inexpensive and lasting.

20 Additional objects and advantages of my invention will be apparent from a reading of the following description taken in connection with the claim and the drawings illustrating the invention wherein—

Figure 1 shows a side elevation of my 25 railroad tie—the rails shown in transverse section.

Fig. 2 is a transverse view partly in section.

Fig. 3 is a modified view of the tie showing a single instead of double construction.

Fig. 4 is a plan view of the assembled members, and

Fig. 5 is a view of the disassembled units of the locking mechanism.

35 Numeral 6 refers to the usual rails of standard or other gage, used for railroads, street car tracks, etc.

To hold the rails 6 parallel, I provide a metal tie 7 shown of a two unit section 8 in 40 Figs. 2 and 4 or in a single unit section 9 in Fig. 3.

This tie 7 is preferably of metal which may slightly expand if necessary though its coefficient of expansion does not have

to be the same as that of the steel rails; 45 furthermore by making the ties of metal all can be of uniform size and thickness. The ties 7 are made **U** shape in cross section and inverted as shown at 9 to provide a resilient or an easy riding seat, also for the 50 accommodation of a brace or standard 10. This brace 10 has a groove 11 to hold a screw threaded rod 12 having a head 13 and nut 14. Threaded on the worm 12 is a riding nut 14, having an ear or clamp 15, co- 55 operating with another nut 16 having ear 17. These ears 15 and 17 rest against flanges 18 of the rail 6. When nuts 14 and 16 are forced together by means of a key or wrench 19, acting on head 13 of the 60 worm 12, the rails are held firmly in place and in parallelism by means of aligned slots 20.

I do not wish to limit myself to the double supporting members shown in Fig. 2 or the 65 single unit support shown in Fig. 3. The principle of my invention is the same in both cases.

Furthermore, it must be understood that only a preferred embodiment of my invention is herein shown and described and any departure from the same, such as in shape, size or arrangement of parts may be resorted to without departing from the spirit 70 of the invention or from the spirit and 75 scope of the subjoined claim.

Having thus described my invention what I claim and desire to secure by Letters Patent is:

A railroad tie having slots, an inverted 80 **U** shape brace in each end of said tie under each slot, each brace having a groove, a screw threaded member resting in said groove, means on the member for engaging a rail and means to hold a rail at each end 85 of the tie in parallel alinement.

ELLERY PERRY.
